UNITED STATES PATENT OFFICE.

SAMUEL FURMAN, OF WORCESTER, MASSACHUSETTS, ASSIGNOR TO UNITED STATES ENVELOPE COMPANY, OF SPRINGFIELD, MASSACHUSETTS, A CORPORATION OF MAINE.

MACHINE FOR MAKING WINDOW-ENVELOPE BLANKS.

Application filed August 24, 1918. Serial No. 251,301.

To all whom it may concern:

Be it known that I, SAMUEL FURMAN, a citizen of the United States, residing at Worcester, in the county of Worcester and 5 Commonwealth of Massachusetts, have invented a new and useful Improvement in a Machine for Making Window-Envelope Blanks, of which the following, together with the accompanying drawings, is a specification.

The present invention relates to improvements in machines for making window envelope blanks, sometimes known as "patching" machines. In such machines the envelope blanks, having previously cut window openings therein are each subjected to a patching operation, which consists in adhesively applying a strip or patch of transparent paper to the inside face of the blank, 15 in order to cover the window opening therein. The apertured blanks thus patched are thereupon discharged from the machine, and are collected or stacked in suitable form for the subsequent operation thereon of folding instrumentalities contained in the same or 20 in another machine, as the case may be.

The present invention is concerned only with the operation of patching, and hence no reference need be made to the instrumentalities employed for folding the blanks 30 after they have been patched. The invention contemplates the provision of a patching machine which is readily adjustable and adaptable for use with blanks of various sizes and shapes, with the window apertures 35 in said blanks of various sizes and located in various positions relative to the lines of fold of the completed envelope. This renders the machine substantially universal, in 40 respect to its capability of handling blanks for the manufacture of odd and unusual sizes and shapes of envelopes, which depart from the ordinary commercial types of envelopes in size and in shape as well as in the 45 relative location and width of the windows therein. To this end, the machine of the present invention embodies a novel adjustment of the gumming devices which provide for the adhesive application of the patches 50 to the blanks, and in cooperation therewith, a novel adjustment of the mechanism for producing the transparent patches, whereby the widths of the same are variable, to cor-

respond with variations in the sizes of the windows in the blanks.

In cooperation with the aforesaid mechanism for producing the transparent patches, the machine of the present invention embodies instrumentalities designed to render said patch producing mechanism inoperative 60 in the absence of a blank to which a patch can be applied; in other words, in the event of a failure in the blank feed, there is no stoppage of the machine, but merely a cessation in the production of patches until 65 the blank feed is resumed. The machine of the present invention also contemplates the provision of mechanism for stopping the feeding of blanks when a failure in the supply of blanks is imminent, thereby warning 70 the operator of the necessity for replenishing said supply. Other and further objects of the invention will be apparent as the description proceeds, reference being had in this connection to the accompanying drawings, in which—

Fig. 1 is a top plan view of a machine constructed in accordance with the invention.

Fig. 2 is a front view of said machine. 80

Fig. 3 is a side view of the machine.

Fig. 4 is a central sectional view of the machine.

Fig. 5 is a detail sectional view, on an enlarged scale, of certain of the instrumentalities embodied in the patch producing mechanism. 85

Fig. 6 is a detail view of the adjustable gumming devices of the machine, and

Fig. 7 is a similar view to Fig. 6, illustrating the use of interchangeable gumming devices of different lengths. 90

Like reference characters refer to like parts in the different figures.

The mechanism is supported and carried 95 by and between a pair of longitudinal side frames 1, 1, which provide journals for a main driving shaft 2, the latter being actuated by a belt or other driving device, not shown, from a suitable source of power. 100 The rotation of shaft 2 is communicated by gearing 3 to a shaft 4, which carries a plurality of disks 5 that serve for the conveyance of successive blanks into position for the adhesive application of patches thereto. 105 To this end, the stack of blanks 6 is sup-

ported on a suitable adjustable table 7, with the uppermost blank of the stack in position to be operated upon by a device for separating said uppermost blank from the remainder of the stack and presenting it to the disks 5, 5.

Said device, in the present instance, is shown as an oscillating suction pickup 8, which is carried by a rock shaft 9 and has a suitable flexible connection 10 with the usual vacuum producing and controlling devices, not shown, that are common in mechanisms of this class. The rock shaft 9 has secured thereto an upwardly extending arm 11, Fig. 3, which carries on its free end a roll 12 that is adapted to engage a cam 13 on the shaft 4. Another arm 14, extending forwardly from said rock shaft 9, has secured thereto a spring 15, which normally holds the roll 12 against the cam 13. The oscillations of rock shaft 9, under the influence of cam 13, causes the suction pickup 8 to descend into contact with the uppermost blank on table 7, as shown in Fig. 4, and at this time a suction is exerted through the pickup device so as to seize said blank and separate it from the remainder of the stack. Thereafter, the cam 13 causes the pickup to rock upwardly so as to carry the edge of the blank into a position to be seized by a gripping device on one of the disks 5, as hereinafter described.

The arm 14 oscillates between a pair of adjustable stops or set screws 16, 16' carried by a slidable plate 17, which is adapted to have an up and down movement limited by the travel of a slot 18 therein with respect to a fixed screw or pin 19 carried by the framework. The lower end of plate 17 has pivoted thereto at 20 a pawl 21, which is pressed downwardly by a spring 22. The tooth 23 at the free end of said pawl is thus held in engagement with the teeth of a ratchet wheel 24, which is carried by a shaft 25 that is journaled between the side frames 1, 1 of the framework and below the table 7. Adjacent the pawl 21 is a second pawl 26, having a fixed pivot 27, and having its tooth 28 also adapted to engage the teeth of ratchet wheel 24. The pawl 26 is normally held in engagement with the ratchet wheel 24 by means of a spring 29, which is secured to an extension 30 of said pawl on the other side of its fixed pivot 27, and the pawl 26 thus normally operates as a holding pawl, adapted to retain the wheel 24 and shaft 25 in the position to which they are moved by the upward movement of pawl 21, during the interval that said pawl is moving downwardly with the plate 17, preparatory to its next successive operative stroke.

The shaft 25 carries a pair of spur pinions 31, 31 near the ends thereof, and these pinions are in mesh with racks 32, 32 depending from the table 7, which, as shown in Fig. 2,

is adapted to move vertically on suitable guides or rods 33 carried upon the fixed framework. It will thus be seen that the rotation of shaft 4 is transmitted, through the reciprocating plate 17 and pawl and ratchet mechanism above described, to elevate the table 7 by a step by step movement in the normal operation of the machine, and thereby to maintain the stack of blanks on said table always in position to be operated upon by the suction pickup 8, notwithstanding the continuous removal of blanks from the top of said stack. The extension 30 of holding pawl 26 carries a pin 34 which is received within an elongated slot 35 of an upwardly projecting link 36. The link 36 is pivotally secured at its upper end, at 37, to a lever arm 38 which is pivoted at 39 to a stationary cross bar 40 of the fixed framework. The lever arm 38 has a handle 41 at its free end which is employed in rocking it about its pivotal axis 39, for imparting movement to the pawl 26 through the link 36. Extending at right angles to the lever arm 38 is a sliding latch rod 42, which has an inclined lower edge 43 cooperating with a shoulder 44 on the upper edge of lever arm 38 and near the free end thereof. The latch rod 42 is supported for sliding movement by means of pins or screws 45 carried by the framework and projecting through elongated slots 46 in said rod 42, the latter being urged outwardly by a tensile spring 47, and being adapted for inward movement against the force of said spring by the exertion of pressure on a knob 48. In the position of the parts shown in Fig. 3, the knob 48 has been pressed inwardly, thereby causing the free end of lever arm 38 to be elevated, under the influence of a spring 49, since the outer end of the inclined edge 43 is, under these conditions, in contact with the shoulder 44. This position of the parts holds the pawl 26 in operative relation to the ratchet wheel 24, and is thus the operative position for the intermittent elevation of bed or table 7, as above described.

When the handle 41 is seized by the operator, and the lever arm 38 swung downwardly, the latch rod 42, under the influence of spring 47, moves outwardly, and owing to the incline of the edge 43, locks the said lever arm 38 in its depressed position. In this depressed position, the pawl 26 is held inoperative with respect to the ratchet wheel 24, so that there is nothing to prevent the reverse rotation of shaft 25 which takes place owing to the gravity descent of bed 7 from the position to which it has been elevated. In this connection it is to be noted that the movement of pawl 26 into its inoperative position automatically prevents further operation of pawl 21, since the latter, disposed directly above the former, is carried out of engagement

with the wheel 24 by the contact of the holding pawl against its lower edge. It will thus be seen that the feeding of blanks from the table 7 can be discontinued at will by the operator merely by depressing the handle 41, and furthermore, that after this is done, the machine will not begin to feed blanks again until the knob 48 is pressed inwardly, so as to cause the parts to again 10 resume the positions illustrated in Fig. 3.

The extension 50 of the lever arm 38, on the other side of its pivotal axis 39, lies in the vertical path of a member 51, pivotally secured to the bed 7 at 52 and resting, 15 as shown in Fig. 2, against a pin 53 carried by said bed. In the operation of the machine, as the height of the stack of blanks on bed 7 is gradually decreased, said bed is correspondingly elevated, and when there 20 are only a few blanks left on the bed 7, there would be danger in further elevation owing to the approach toward bed 7 of a member 6', which rests by gravity on the stack of blanks and extends into the opening provided by the windows thereof. In other 25 words, this member 6' which is used to maintain the blanks of the stack in true alinement, and also to prevent the separation from the stack of more than one blank 30 at one time, must, for the performance of its functions, be supported solely by the stack and therefore the stack must not be allowed to get so low that the bottom 50' of said member 6' will strike the support or bed 7. 35 To prevent the supply of blanks from running so low as to bring about the above condition, the member 51 is so disposed as to make forcible contact with the extension 50 at a predetermined point in the elevation of 40 the bed when the height of the stack has been decreased to a safe limit, and this forcible contact rocks the lever arm 38 downwardly, and thereby automatically causes the gravity descent of the bed and the discontinuance 45 of the blank feed. The operator is thereby warned to replenish the stack of blanks on the bed 7, and thereafter he can cause a resumption of the blank feed simply by pushing in the knob 48 as above described.

The suction pickup 8 is, as above described, movable in unison with the arm 14 about the same pivotal axis. As a result of this construction all possibility of too great an elevation of the table 7 and stack of blanks is eliminated; that is to say, the rotation of shaft 25 will always be automatically discontinued when the stack is high enough to be reached by the down stroke of the pickup. This is true for the reason that the top of the stack of blanks acts as a limit to the downward movement of suction pickup 8, as effected by the low portion of cam 13. If the top of the stack 55 is so high as to prevent the full downward

movement of the pickup, this will also prevent the contact of arm 14 with the lower stop 16', and hence will prevent the operative reciprocation of plate 17 until enough blanks have been picked off to allow the full 70 stroke of the pickup.

Each blank as seized by the suction pickup 8 has its adjacent edge presented to a gripping device, preferably carried by the middle disk 5 on shaft 4. Said disk 5 is 75 preferably recessed on its periphery, as indicated at 54, Fig. 4, and has journalled eccentrically therein a shaft 55 which extends therethrough and through the other disks 5, 5 toward one side of the machine, and carries on its end an arm 56 having a roller 57 thereon adapted to contact with an interior face cam 58. The shaft 55 is surrounded by a spring 59 which has one end secured thereto, and the other end secured to an arm 60 which rotates in unison with said disk 5 and shaft 4, so that said spring 59 always tends to return the shaft 55 to its normal position after the rocking of said shaft by the contact of roller 57 with cam 58. The cam 58 is so set with respect to the rotation of shaft 4 as to sharply rock said shaft 55 just as a blank is presented by suction pickup 8 to the disk 5, thereby causing the pinching of the edge of said blank by a gripper member 61 carried by shaft 55 and operating in the recess 54. The gripper 61 and disk 5 thus draw the blank from beneath the pickup 8, whose suction may be automatically discontinued at the proper moment to release the blank, and then resumed for the seizure of the next succeeding blank by mechanism well known in the art, which forms no part of the present invention.

For accomplishing a rapid movement of 105 gripper 61 in seizing and releasing the edge of the blank, the cam 58 is adapted to be oscillated so as to approach the roller 57 as the latter is swung into contact with said cam, and thereby to accelerate the travel of 110 said roller over said cam. To this end, the cam 58 is journalled loosely on the shaft 4 and has pivotally secured thereto at 58' a rod 59', which is bifurcated at its end to embrace and be guided by shaft 2, said rod 115 carrying a roll 60' which makes contact with a cam 61' on shaft 2. A spring 61'' holds the roll 60' in contact with cam 61', which is so timed as to oscillate the cam 58 at the proper period to accelerate the opening and 120 closing movements of gripper 61.

Each blank thus seized by the gripper 61 is carried by the disks 5 into a position above the shaft 4, and at this point the gripper 61 is released by the reverse rotation of shaft 55 under the influence of spring 59 and cam 58, as will be well understood. Coincident with this release of the blank, its edge passes into the bite of disks 62 cooperating with the disks 5 to advance 130

- the blank rearwardly of the machine in the plane of its horizontal position. The disks 62 are carried on a shaft 63 which is driven by suitable gearing, not shown, from the shaft 4. From this point rearward in the machine, the travel of each blank is in the plane of its horizontal position, the inner face of the blank being uppermost, so as to permit the application of a band of adhesive around the margin of the window opening in the blank and the subsequent securing of a patch to cover said opening. The blank is guided in its horizontal movement between spaced upper and lower guides 64, 64 which are supported at their rear ends by transverse shafts 65, 65, journaled in the side frames 1, 1, and having cooperating feed disks 66, 66 theron for continuing the horizontal travel of the blank.
- Intermediate the blank feeding disks 5, 62, and 66, 66 are disposed the gumming instrumentalities of the machine, for applying a band of adhesive around the margin of the window opening in the blank while said blank is in transit between said feeding disks. A shaft 67 driven by suitable gearing, not shown, from the main shaft 2, carries disks 67' and a segmental member 68, the latter being adjustably secured to said shaft by means of a set screw 69. The member 68 provides for the support of adjustable and interchangeable gumming die members which are supplied with gum from a transfer roll 70, operating in conjunction with a gumming roller 71 disposed in a gum box 72. Along its advancing edge the member 68 is adapted to have secured thereto by means of screws 73, a fixed gumming die member 74, which constitutes one longitudinal edge of the die for gumming the margin of the window in the blank. Said member 74 is made removable from the segmental member 68 for the purpose of substituting a similar member 74 of greater or less length, as required by the length of the window opening in the particular form of blank which in any given instance is being run through the machine. As shown in Figs. 6 and 7, the machine is equipped for this purpose with a plurality of lengths of fixed gumming die members 74.
- For cooperation with the members 74, the machine provides a plurality of gumming die members 75 of corresponding lengths as shown in Figs. 6 and 7, each adapted to constitute the other longitudinal edge of the die for gumming the margin of the window opening. When in position on the segmental member or support 68, the member 75 is angularly adjustable toward and away from the member 74 by means of screws 76, which pass through elongated slots 77 in said member 75. The width of the window gumming die thus constituted by members 74 and 75 is therefore variable to suit vari-
- ous sizes of windows, and obviously the members are interchangeable to compensate for variations in the lengths of said windows. Each fixed die member 74 has a rearward extension 78 at each end of a depth 70 corresponding to the narrowest window, so as to provide for gumming at the ends of the windows in the blanks. When the member 75 is adjusted for a window of greater width, the end extensions 78 may readily be increased in length by the attachment to flanges 79 of member 74 of various size strips 80, as shown in Figs. 6 and 7, which are temporarily held in place by screws 81.
- Below the shaft 67 is journaled a shaft 82, the latter being driven from shaft 67 by suitable gearing, not shown. The shaft 82 is adapted to have secured thereto the bed or platen cylinder which cooperates with the gumming members 74 and 75 carried by the segmental support 68. As herein shown, the cylinder is made in two parts, 83 and 83, which are secured together and to the shaft 82 by any suitable means such as screws, not shown, the two-part construction being adopted to permit its ready removal from the shaft 82 when it is desired to substitute a similar cylinder of different length, it being understood that, as in the case of the die members, a plurality of lengths of cylinder 95 pieces 83, each with suitable grooves 84, to match with the extensions 78, are provided. The surface of the two-part cylinder is formed with a plurality of longitudinal grooves 85, 85, the latter being so spaced as to register, by pairs, with the die members 74 and 75 in the several positions of adjustment of the latter for windows of different widths. To this end the bed cylinder 83, 83 is adjustably secured to the shaft 82 by means of a set screw 86, so that it can be turned thereon to bring the proper grooves 85 into position for cooperation with the gumming die. In other words, one groove 85 may be used in conjunction with any other groove to obtain the desired width, and thus with only six grooves, as shown in Fig. 4, a great number of variations are possible.
- In advance of the feed disks 66, which seize the blank after it has been gummed around the margin of its window as above described, is disposed a shaft 87 which is operated by suitable gearing, not shown, from the main driving shaft 2. Said shaft 87 has secured thereto at one end a crank arm 88, Fig. 3, which provides a slot 89 for the adjustable attachment of a block 90. The block 90 has pivotally secured thereto at 91 a rack bar 92, the free end of which slides in a guideway 93, Fig. 5, which is provided by a bracket 94 that is suspended from a shaft 95. The shaft 95 is journaled in bearings 96, 96 that are provided by rearwardly extending brackets 97 secured to a 130

transverse rear member 98 of the fixed rial 114 step by step to suitable cutting de- framework. The block 90 is adjustable in the slot 89 as will be well understood, to vary the throw of the sliding rack bar 92 which 5 is reciprocated by the rotation of shaft 87. The teeth of rack bar 92 are constantly in mesh with the teeth of a gear 99, which is loosely journalled on the shaft 95, said gear having on its vertical inner face a plurality 10 of ratchet or clutch teeth 100. Adjacent the gear 99, the shaft 95 has secured thereto, by means of a key 101, a collar 102, and on an extension 103 of the hub of said collar is slidably mounted a ring 104. The ring 104 has 15 secured thereto an outwardly projecting pin 105, which passes slidably through an opening therefor provided in the collar 102, with the end of said pin bevelled off to provide a tooth 106 adapted, as hereinafter described, 20 to make operative contact with the ratchet or clutch teeth 100 on the inner face of gear 99. A spring 107, surrounding the pin 105 in the opening of collar 102, bears against a shoulder of said pin and normally tends to 25 press said pin in the direction of the ratchet or clutch teeth 100 of gear 99. The ring 104 provides a peripheral groove to receive a pair or diametrically opposite lugs 108, 108, which extends inwardly from the end of a 30 yoke 109 that loosely embraces said ring. The yoke 109 is pivoted to the fixed framework at 110, and on the other side of its pivotal axis has an inwardly curved arm 111 which carries a roll 112 in contact with a 35 face cam 113 on shaft 67. In the rotation of said shaft, the yoke 109 is oscillated to cause inward and outward movement of the ring 104 on hub extension 103, thus alternately moving the tooth 106 into and out of 40 engagement with the clutch or ratchet teeth 100 on gear 99. When the tooth 106 is engaged, the collar 102 and shaft 95 are driven in unison with the rotating gear 99, and the parts are so timed that this driving engagement 45 takes place on that stroke of the rack 92 which will produce a clockwise rotation of gear 99; on the reverse stroke of said rack, the tooth 106 is withdrawn, and hence the shaft 95 remains stationary, being so 50 held by a friction brake 102' on the periphery of collar 102.

The shaft 95, thus intermittently rotated in the normal operation of the machine, is utilized for the feeding of the transparent 55 material which is used to cover the gummed window openings of the blanks. Said material is drawn in a continuous strip 114 from a supply roll, not shown, which strip after passing over suitable guide and tension 60 devices 115, is fed beneath a roll 116 which is secured to the intermittently rotating shaft 95. Beneath the roll 116 is journalled a roll 117 which is driven in unison with roll 116 by gearing 118, the two rolls 116 and 65 117 cooperating to advance the patch mate-

rial 114 step by step to suitable cutting devices which sever a window patch of the desired width from the end of the strip 114, as hereinafter described. In the normal operation of the machine, the intermittently 70 operating patch material advancing mechanism, above described, functions with regularity and in timed relation to the movement of blanks through the machine, so that a predetermined length of said material, corresponding to the width of a patch, is fed forward by rolls 116 and 117 at the proper moment to be cut off and conveyed into contact with the gummed window opening of a blank that has been at the same time withdrawn from the stack on table 7.

It sometimes happens that there is a failure in the blank feed, due to imperfect functioning of the suction pickup 8, or to any other cause, as when the table 7 is lowered, either automatically or by the operator. Under these circumstances, the production of a patch, in the usual regularity of operation of the machine, would not only be superfluous, but would tend to clog the 90 machine and cause a wastage of material. According to the present invention, the operation of the intermittent patch feeding mechanism is made in every instance dependent upon the presence of a blank in actual transit through the machine; in the absence of such blank, the patch material, which would ultimately be applied thereto, is not fed forward by the rolls 116, 117, but instead said rolls are maintained inoperative 95 until a blank is actually on its way. The devices employed for this purpose will now be described in detail.

A shaft 119, journalled in bearings 120, 120 on the front of the machine, has secured at 105 its central portion a depending arm 121 which provides a plurality of spaced detecting fingers 122, 122 in proximity to the disk 5 which carries gripper 61. Said shaft 119 is adapted to be oscillated through a limited 110 arc by means of a reciprocating rod 123, which carries a roll 124 that engages a cam 125 on shaft 67. The rod 123 is guided in its reciprocating movement by its bifurcated end which embraces shaft 67, and also 115 by an elongated slot 126 therein which works over a pin 127 projecting from the fixed framework. The end of the rod 123 is adapted to make contact with an arm 128 depending from the shaft 119, said arm 128 120 having secured thereto a light spring 129 which tends to rock the shaft 119 in a direction to throw the fingers 122 inwardly, one on each side of the central disk 5. An arm 130 projecting upwardly from shaft 119 is 125 connected to a sliding rod 131 that projects rearwardly into proximity to arm 111 of yoke 109.

The connection between arm 130 and rod 131 is a lost motion connection; that is to 130

say, the rod 131 provides an elongated slot 132, which receives a pin 133 that is carried by the free end of the arm 130. A spring 134 is connected at one end to said pin and at the other end to a pin 135 carried by rod 131, the tendency of the spring being to draw the pin 133 to the left in said slot. As shown in Fig. 3, the pin is disposed at the right hand end of the slot, due to the engagement of a blank by the fingers 122, 122. The cam 125, acting through rod 123, arms 128 and 130 and the above described pin and slot connection, imparts reciprocation to the rod 131, the inner end of which is guided in a suitable guideway 136 of the fixed framework. Said inner end has a reversely extended hook portion 137 which is adapted to cooperate with a reciprocating plate 138 that is adapted to slide in a bracket 139. Said plate 138 is pivotally connected at 140 to the arm 111 of the pivoted yoke 109, so that the oscillations of said arm 111 under the influence of cam 113 cause the transverse in and out movement of said plate 138 in timed relation to and without interference by the movement of the adjacent hook portion 137 of rod 131.

The above condition holds true when a blank is undergoing conveyance by the disks 5, 5 and gripper 61. In other words, the fingers 122 are drawn lightly inward against the surface of the blank by the light spring 129, and the contact of said fingers with the blank prevents the arm 128 from following the final inward and upward movement of rod 123, which latter proceeds independently under the influence of a spring 141. This limiting of the oscillation of shaft 119 thus limits the forward travel of rod 131, so that hook 137 does not move far enough toward the plate 138 to interfere with the regular reciprocation of the latter. The forward and downward stroke of rod 123, under the influence of cam 125, effects the movement outward of fingers 122 in time to prevent the engagement of said fingers with the margin of the window opening in the blank and thus tearing of the window is prevented. However, when there is a failure in the blank feed, there is nothing to prevent the full inward movement of said fingers 122, since the arm 128 can follow the rod 123 to the limit of its inward and upward movement. This increased counter-clockwise rotation of shaft 119, Fig. 3, causes the pin 133 to engage the forward end of slot 132 and thereby draws the rod 131 to the left, so that the hook 137 is interposed in the path of movement of the plate 138. As a result, the spring 142, which acts on arm 111 to hold the roll 112 against cam 113, is rendered ineffective to carry said roll against the lowest portion of said cam, and hence the degree of oscillation of yoke 109 about pivot 110 is appreciably reduced.

This reduction of movement prevents the tooth 106 from reaching the teeth 100 of gear 99, and thereby causes an interruption in the operation of the intermittent patch material feeding means. Such an interruption continues until the feed of the blanks is resumed, whereupon the hook 137 is withdrawn to permit the full reciprocation of plate 138. In this way, whenever there is a failure of the blank feed, or whenever the bed 7 is caused to descend, either automatically or at the will of the operator, there is brought about a discontinuance in the operation of the intermittent patch material feeding mechanism, so that no patches are produced during the absence of blanks from the feed disks 5, 5.

In the normal operation of the machine, however, the patch material is intermittently advanced by the rolls 116 and 117 so that its end projects a predetermined distance, at each operation, beyond the stationary member 143 of a cutting mechanism, said end being projected over an inclined guide plate 144 so as to be substantially tangent to the surface of a cylinder 145 that is carried by the shaft 87. The inclined plate 144 is supported in proximity to the cylinder 145 by means of brackets 146, 146 that are carried on a transverse rod 147 of the fixed framework. For cooperation with the plate 144 is provided a patch material holding member 148 which depends from arms 149, 149 that are secured to a rock shaft 150, carried in brackets 151, 151 of the fixed framework. The cam 152 on shaft 87 is operable through an arm 153, Figs. 1 and 3, to rock the shaft 150 at intervals so as to carry the member 148 down into contact with the patch material on the plate 144, so as to securely hold said patch material in the position to which it has been advanced, in readiness for the operation of the patch severing mechanism, which will now be described.

For cooperation with the forward cutting edge of member 143 is provided a knife 154, which is carried by a bar 155 that is pivoted on a shaft or trunnion 156, supported in a bearing 157 on the rear member 98 of the fixed framework. On the other side of its pivotal support, said bar 155 has an extension 158 that is connected pivotally and universally, at 159, to a rod 160. The rod 160 is pivotally connected at its lower end at 161 to a lever 162, Fig. 4, which is itself pivoted on the lower shaft 65. The lever 162 carries a cam roll 163 which is held by a spring 164 in engagement with a cam 165 on shaft 87. By the operation of said cam and lever, the bar 155 is rocked at predetermined intervals to cause a severing cut of knife 154 against the forward edge of member 143, said edges being maintained in close contact by a spring 166 that forces the bar 155 rearwardly. The holding member 148 presses 130

the patch material against plate 144 during the cutting of said material by the knife 154, thereby preventing displacement of the severed patch and at the same time affording sufficient tension on the material to prevent its deflection when engaged by the knife edge. The severed patch is held by the member 148 in position to be seized by suitable engaging and gripping devices carried by the rotating cylinder 145, so as to convey said patch into contact with the horizontally travelling blank to which it is to be applied.

It is to be noted that the patch producing mechanism, involving as above described, a patch material feeding means and a patch severing means, is adjustable to vary the width of the patches cut off, so as to maintain the proper relation between said patches and the windows of the blanks that are, in any given instance, being run through the machine. It has been shown that the window gumming devices are adjustable both as to width and as to length, and obviously, it is wholly desirable that the patches for application to the windows be correspondingly variable in size. The length of each patch is, of course, determined by the width of the supply roll of patch material, and the patch handling devices, feed rolls and severing means are made of sufficient extent transversely of the machine to handle patches varying from the minimum to the maximum length. The width of each patch, on the other hand, is a function of the feeding and severing means, and these mechanisms in the present machine are so disposed as to permit the necessary variation in the width of the patches without affecting the extent to which each patch is projected beyond the plate 144 for seizure of its edge by the gripping devices of conveying cylinder 145.

To this end, said plate 144 is fixed in its relation to the periphery of cylinder 145, by its attachment to the cross rod 147. On the other hand, all of the other patch handling instrumentalities, except the holding member 148, are adjustable forwardly and rearwardly of the machine, said instrumentalities being supported on the rear frame member 98, which has extensions 167, 167 by which it is attached to the side frames 1, 1. The extensions 167, 167 have elongated slots 168 therein through which extend holding bolts 169, that are adapted to be loosened when desired to permit the forward or rearward movement of member 98 and the patch feeding and cutting devices carried thereby. It will be seen that the width of the patches is reduced by a forward movement, and is increased by a rearward movement, of these various instrumentalities. To accommodate the operating parts to such movement, they are, wherever necessary, adjustable as to length; it has already been shown that the block 90 is adjustable in the crank arm 88 to

vary the throw of the rack bar 92, and similarly the yoke 109 has an adjustable slot connection 170, Fig. 1, with the arm 111, so as to permit the shortening or lengthening of said yoke, depending upon the position to which the member 98 is moved. The universal connection 159 of the knife bar 155 compensates in a similar manner for the forward or rearward movement of the severing mechanism without affecting the operation thereof. It will be obvious that, if desired, graduations may be marked on the relatively fixed and relatively movable elements of one or more of these adjustable connections, as for instance the connection 170, whereby the desired width of the patch may be employed to exactly determine the setting of the parts.

The cylinder 145 provides cutaway portions 171 for the operation of grippers 172, 172, which are substantially similar to the gripper 61 of the blank conveying mechanism. Said grippers 172 are carried on a shaft 173, journalled eccentrically in cylinder 145 and operated in a manner similar to the shaft 55 by a spring 174, cam 175, cam roll 176 and arm 177. The cam 175 is oscillated in a manner similar to the cam 58, and for the same purpose, by a rod 178 carrying a cam roll 179 that is held in contact by a spring 180 with a cam 181 on shaft 67. Adjacent the grippers 172, 172, the cylinder 145 carries a pair of outwardly projecting spring pressed spurs 182, 182, and said grippers at their free ends have recesses or openings to receive said spurs.

In the counter-clockwise rotation of the cylinder 145, the grippers 172 lie retracted in their cutaway portions 171 until they have just passed the forward edge of plate 144. At this point the shaft 173 is rocked quickly by cam 175 to cause the grippers to seize the projecting edge of the patch, which at that time is released by the holding member 148. The edge of the patch is pinched between the grippers and the surface of cylinder 145, and said patch is impaled on the spurs 182 by this pressing action. As the cylinder 145 continues to rotate, the shaft 173 is reversed, to draw the grippers inwardly of their cutaway portions 171 and thereby to release the patch, which however is still held in proper registered position on the cylinder 145 by reason of its impalement by the spurs 182. The patch is thus conveyed downwardly on the cylinder 145, and it reaches the bottom of its movement in timed relation to the arrival of a blank, as projected horizontally rearward by the feed disks 66, 66. Below the cylinder 145 is a cooperating cylinder 183, and the contact of the spring pressed spurs 182 with the surface of cylinder 183 causes said spurs to be pressed inwardly, thereby releasing the patch, and permitting its adhesion to the gummed margin of the window in the blank, which reaches this

130

point at just the proper time to have the patch rolled into contact therewith. The passage of the blank and patch in unison between the cylinders 145 and 183 affords sufficient pressure to complete this adhesion, and the blank thus patched is discharged by said cylinders onto a suitable table or support, not shown.

I claim,

10 1. In a machine of the class described, means for gumming around the opening of a window envelope blank, comprising a rotatable gumming die support, a longitudinal gumming member having a fixed position on said support, a second longitudinal gumming member adjustable toward and away from said first gumming member and a rotatable member having a plurality of spaced grooves for cooperation with said gumming members, the spaces between said grooves corresponding to the several adjustments of said gumming members.

20 2. In a machine of the class described, mechanism for applying gum around the margin of the opening in a window envelope blank, comprising a cylindrical support, with a relatively fixed longitudinal gumming member, a second longitudinal gumming member parallel with said fixed member, means for adjusting said second member toward and away from said fixed member and a rotatable grooved cylinder for cooperation with said gumming members, and means for adjusting said cylinder angularly about its axis of rotation to procure cooperation of the grooves thereof with said gumming members.

30 3. In a machine of the class described, a gumming mechanism for applying a band of adhesive around the margin of an opening in a window envelope blank, comprising a rotatable gumming die adjustable in width, a rotatable cylinder for cooperation with said die having a plurality of differently spaced grooves, the spaces between said grooves corresponding to the various widths obtainable by the adjustment of said gumming die, and means for adjusting said cylinder angularly about its axis of rotation, to procure cooperation of the grooves thereof with said gumming die.

40 4. In a machine of the class described, a rotating member adapted to procure the movement of successively fed apertured blanks, means for intermittently feeding a web of patch material for application to the apertures of said blanks, said feeding means for the patch material comprising a reciprocating rack, a shaft, a pinion loosely journaled on said shaft and in mesh with said rack, and means for causing rotation of said shaft by said pinion upon alternate reciprocations of said rack, in combination with means associated with said rotating member,

for preventing the operation of said feeding means for the patch material in the absence of a blank in transit through the machine upon said rotating member.

5. In a machine of the class described, the combination with blank advancing means, of synchronously operating devices for producing patches to be applied to said blanks, said last named means comprising a pair of rolls for intermittently advancing a web of patch material, a reciprocating rack, 75 a pinion in mesh with said rack, and means for procuring a driving engagement between said pinion and said rolls in one direction only of rotation of said pinion, and means, comprising fingers for engaging the 80 blanks on said blank advancing means, for preventing effective operation of said rolls in the absence of a blank in motion on said advancing means.

6. In a machine of the class described, 85 means for advancing successive apertured window-envelope blanks, means for intermittently feeding a web of material for formation into patches to be applied to the apertures of said blanks, means for detecting 90 the presence of a blank in motion on said advancing means, and means operable by said detecting means for interrupting the intermittent feed of patch material in the absence of a blank in motion on said advancing means.

7. In a machine of the class described, the combination with means for feeding blanks, of means for conveying patches into contact with said blanks, means for feeding 100 a web of patch material, means for cutting off patches from said web, and means for adjusting the position of said patch feeding and patch cutting means relatively to said patch conveying means, whereby to vary the 105 width of the patches produced.

8. In a machine of the class described, means for feeding blanks, and means for conveying patches into contact with said blanks, in combination with means for producing successive patches from a continuous web of patch material, said patch producing means being adjustable, relatively to said patch conveying means, whereby to vary the 110 widths of said patches.

9. In a machine of the class described, means for feeding blanks, and means for conveying patches into contact with said blanks, in combination with means for intermittently feeding a web of patch material and means 115 for cutting off successively fed portions of said web to form patches, said web feeding and web cutting means being adjustable in unison, relatively to said patch conveying means.

10. In a machine of the class described, means for feeding blanks, and means for conveying patches into contact with said

blanks, in combination with means for cutting successive patches from the end of a web of material, means for intermittently feeding said web, in advance of each cut, to 5 a predetermined position with respect to said conveying means, means for adjusting the position of said cutting means relatively to said conveying means, and means for varying the feed of said web in accordance 10 with the position of adjustment of said cutting means, whereby patches of different widths will be produced.

11. In a machine of the class described, the combination with means for advancing 15 apertured blanks, means for applying a band of gum around the margin of the aperture in successively advanced blanks, means for adjusting said gum applying means to conform to the size and shape of the aper- 20 tures in said blanks, means for seizing and conveying patches into contact with the gummed portions of said blanks, means for producing said patches from a continuous web of material, and means for adjusting 25 said patch producing means in conformity with said gum applying means, to present

patches of different widths to said seizing and conveying means.

12. In a machine of the class described, a gumming die support, comprising a device 30 adapted to receive and have fixedly secured thereto, interchangeably, longitudinal window gumming members of different lengths, and means for adjustably securing said device, interchangeable die members corre- 35 sponding to said fixed members.

13. In a machine of the class described, a gumming mechanism comprising a device adapted to receive and have fixedly secured thereto, interchangeably, longitudinal win- 40 dow gumming members of different lengths in combination with a rotatable shaft adapted to receive and have secured there- to, interchangeably, cylinders of different lengths corresponding to the lengths of said 45 die members.

Dated this 20th day of August, 1918.
